(57) **CLAIM**

The ornamental design for a tap as shown and described.

DESCRIPTION

FIG. 1 is a right side view of a tap, showing our new design, with the left side being a mirror image thereof.

FIG. 2 is a top view thereof.

FIG. 3 is a front view thereof.

FIG. 4 is a rear view thereof.

FIG. 5 is a perspective view thereof.

FIG. 6 is a side view of another embodiment of a tap in accordance with aspects of the present subject matter, with the opposing side being a mirror image thereof.

FIG. 7 is a top view of the embodiment of the tap illustrated in FIG. 6.

FIG. 8 is a front view of the embodiment of the tap illustrated in FIG. 6.

FIG. 9 is a rear view of the embodiment of the tap illustrated in FIG. 6; and,

FIG. 10 is a perspective view of the embodiment of the tap illustrated in FIG. 6.

Additionally, contour lines and/or surface shading, to the extent applicable, are illustrated simply for purposes of highlighting the solid-rendering, and, thus, form no part of the claimed design.

Any combination of the illustrated features, including claimed features and unclaimed features, may be claimed in this application or a continuing application claiming priority to this application by converting any portion of the broken lines to solid lines, any portion of the solid lines to broken lines, or both.
